Des. 214,805
Patented July 29, 1969

214,805

GRINDING AND POLISHING DEVICE

William H. Averitte, 2542 NW. 19,
Oklahoma City, Okla. 73107

Filed July 29, 1968, Ser. No. 12,933

Term of patent 3½ years

Int. Cl. D15—05

U.S. Cl. D37—1

FIG. 1 is a perspective view of my novel grinding and polishing device showing the top, front and one side thereof.

FIG. 2 is another perspective view of the device showing the bottom, the opposite side and the back thereof.

FIG. 3 is a front view of the device.

I claim:

The ornamental design for a grinding and polishing device, as shown.
